DRILL BIT

Royal N. Riblet, Spokane, Wash., assignor of
one-half to Hugh Hurlow, Jr., Tacoma, Wash.

Application May 22, 1937, Serial No. 144,269

1 Claim. (Cl. 255—64)

My present invention relates to drill bits of the impact type, which bit, while adapted for use in various ways, is especially designed for drilling blasting holes employed in different forms of excavation work and especially for hard rock drilling in mines or other places.

The primary object of the invention is the provision of a high speed drilling bit in which the cutting members are arranged in such manner as to insure maximum durability for the cutters with which the face of the bit is studded and also to insure maximum efficiency for the bit in the performance of its functions of earth drilling or boring.

15 The invention consists essentially in certain novel combinations and arrangements involving a bit having a shank for attachment to the chuck of the usual type of pneumatic, impact drilling equipment or any other form of machine which, 20 through a series of rapid blows, presents the cutters of the bit against the material operated on to fractionate or reduce the rock or material to a fineness.

Such drill shanks are provided with water holes 25 through which water may be forced to wash away the cuttings reduced by the cutter members on the face of the bit and the cutters are arranged in such a manner that they may be replaced at required intervals and the entire drill bit renewed 30 for continued work without the necessity of returning all of the steel to the blacksmith or tool sharpener, which in most drilling operations requires the double handling of tons of drill steel in order to sharpen the faces of the bits accompanying 35 the steel.

In the accompanying drawing I have illustrated several forms of the invention in which the bit is adapted for work in both hard and soft earth 40 where excavations are to be made, in mines where ore bodies are encountered and usually surrounded by extremely hard rock, in tunnel work, and in all other forms of drilling operations.

It is to be understood that changes and alterations 45 may be made in these exemplifying structures within the scope of my claim without departing from the spirit of my invention.

Figure 1 is a side view of a bit employing my invention disclosing the shank portion of the usual form of drill bit and showing the removable cutters in the working face of the bit.

Figure 2 is an enlarged end view of the drilling bit.

Figure 3 is a view in cross section on the line 55 3—3 of Figure 2 of the head portion or bit.

Figures 4 and 5 are modified forms of my bit, as disclosed in Figure 2.

Figure 6 is a perspective of one of the cutters and Figure 7 is an elevation showing the reduced cutter faces of the group of four successive cutter members.

In the form of the invention shown in Figures 1 and 2 the bit 10 is adapted for boring or drilling in hard rock, granite, and other hard materials, though it is not confined in any sense to particularly hard rock or earth, but is intended for all purpose drilling.

In Figures 1 and 2 four radially mounted replaceable cutters 1, 2, 3, 4, are illustrated, and in Figure 4 cutters 1a, 2a, 3a, 4a are utilized in the face of the bit and held in position by means of soft rivets 12 which are easily removable when occasion demands and which will insure that the cutter members will be held substantially to the bit head 10 forming the supporting means for the 20 cutters. The cutter members are fitted into grooves 13 cut into the head 10 and in the case of the structure disclosed in Figure 2 each cutter provides a stop or gauging means for the adjacent cutter on one side. This is repeated until all 25 cutter members are in contact with each other to form an accurate gauge for the hole being drilled.

The rivets 12 are intended to be loosely fitted into holes 14 in the replaceable cutter members so that they serve for the most part as retainers 30 and not as gauge means for the drilling. The true gauging means as in Figure 2 is provided by forming each cutter member with a slightly bevelled face 15 on its inner end which provides an overlap for one adjacent cutter member and serves 35 as a stop for that cutter member forming a somewhat square hole at the function points of the cutters, this hole being sufficient to permit the flow of water through the shank of the drill and out and around the cutters to wash away the cuttings removed by the cutters.

Another feature of the bit consists in the formation of the cutting faces of the cutters. These cutting faces in each successive cutter have a different width of cutting edge. Thus the cutters 1 and 1a have a full length cutting edge, cutters 2 and 2a each have an edge reduced approximately one-fourth by grinding away the inner cutting edge at 16, cutters 3 and 3a are likewise cut back an increased fractional part of the cutting edge, 50 and cutters 4 and 4a are reduced to approximately one-half of the cutting face in a like manner. While there are four cutters to make up a set of my drill, each one being identical except for the width of the cutting face, one operation 55

for forming these members is to grind away a portion of the edge before the cutters are tempered. Other forms and means may be used to accomplish this purpose.

5 With the drill bit thus mounted with replaceable cutters more rapid drilling is possible and with the assurance of greater clearance for the cuttings or particles removed from the face of the hole. This permits the flow of water to more 10 rapidly pass the particles away from the bit and the chief object accomplished in such a bit as I have herein described is to provide cutting edges that will be equalized in the area of the hole in this manner. The exact center of the 15 bit has little or no travel as the bit rotates during its operation. The cutting edges on the periphery or outside of the bit travel the maximum distance or a distance equal to the circumference of the circle of the bore. Thus in a 20 two-inch bit the outer edge of the cutting face in one revolution of the bit will have travelled slightly more than six inches. A point intermediate between the center and the extreme outer edge of the cutter will travel slightly more 25 than three inches. The cutter edge at the hole of the bit which is approximately one-quarter inch will travel approximately three-quarters of an inch in one revolution. Hitherto bits have been made with all the cutting edges reaching from the central or water hole to the outside 30 or gauge of the tool.

In my construction I eliminate the interior edges of the cutters and substantially equalize the work performed by the cutters over the area 35 of the cut or bore of the hole. Thus all cutters have cutting edges from the gauge point inward and each of the cutters, with the exception of one, has the cutting edge reduced to secure this equalization. In this manner the cutting edges 40 will not be utilized over a part of the surface for grinding up the cuttings after being removed from the rock face resulting in lessened power and increased rapidity of drilling.

In Figure 2 I have disclosed means whereby 45 my bit may be manufactured by milling or forming two right angular channels across the face of the bit 10 to receive the cutters. I have provided holes in the wings of the head to receive a soft rivet which may be readily driven out by 50 proper tools when new or renewed cutters are to be inserted.

In Figure 4 I have shown a somewhat different structure in that the slots or grooves 17 are formed with an end miller which when it has

reached its innermost point will leave a curved end or abutment. The cutters 1a, 2a, 3a, 4a are also formed with a semi-circular or inner end 18 and abutting upon the abutment 19 to establish the desired gauge for the drill bit.

Figure 5 is formed in the same manner as the bit of Figure 2 but the cutter members 11 have their cutting faces of equal length and their abutting ends formed at a slight angle to insure the establishment of a fixed gauge for the cutters and the consequent hole to be drilled.

By reference to Figure 6 showing a perspective of one of the series of cutter members, the cutting edge is indicated at 20, the cut-away portion for clearance and for establishing the principle 15 of my invention being disclosed at 21. The hole 14 for receiving a rivet and a cut-out portion 22 is established on the inner end of the cutter to insure maximum clearance for water as it passes from the water hole or channel through the drill shank. All of the cutters, in a set are formed identical except that the length of the cutting edge 20 is altered to insure that the hole will be presented evenly with cutting faces in accordance with its diameter to insure that the material 20 is cut from the face of the hole and not re-cut or ground during the operation of the drill, thus allowing rapid removal of the cuttings as well as rapid progress in the drilling operation. While 25 I have described in the drawing of my invention a drill bit in one piece with the shank portion of a drill rod I also contemplate the making of my bit in a short length or head which may be secured to a drill rod through the use of threads or any suitable means for joining the short bit section to such a rod.

Having thus fully described my invention, what I claim as new and desire to secure by Letters Patent is:

The combination with a tubular drill rod having an integral open center head comprising two sets of transversely extending radially-grooved wings having transverse holes therein, of a series 40 of cutters fitted in said wings and having holes registering with the wing-holes, readily removable soft-metal rivets secured in the complementary wing-holes and cutter holes, each said cutter having a transversely extending beveled inner end with its edge overlapping an adjoining groove and forming a gage-abutment for another cutter, one of said cutters having a full-length 45 cutting edge, and the remaining cutters having cutting edges of decreasing length.
